FRANCIS W. FURSTENBERGER AND CLYDE C. DEEDS, OF TERRE HAUTE, INDIANA

SHELF ATTACHED ARTICLE SUPPORTING BRACKET

Application filed March 22, 1930. Serial No. 438,212.

This invention relates to the class of supports or brackets, the present device being designed particularly for use in stores for supporting in a conspicuous position an article comprising one of a number upon an adjacent shelf.

The primary object of the present invention is to provide a device which may be readily and firmly attached to the edge of a shelf to project forwardly therefrom for the support of an article to be placed on display.

Another object of the invention is to provide a readily attachable supporting bracket for shelves having a novel means for engaging cans or jars of varying sizes to hold the same firmly against movement.

Still another object of the invention is to provide in a display bracket of the character described a novel means for locking the same with the edge of a supporting shelf whereby the bracket, while adapted to be easily and quickly removed when desired, is held firmly against accidental movement.

The invention will be best understood from a consideration of the following detailed description taken in connection with the accompanying drawings forming part of this specification, with the understanding, however, that the invention is not confined to any strict conformity with the showing of the drawing but may be changed or modified so long as such changes or modifications mark no material departure from the salient features of the invention as expressed in the appended claims.

In the drawings:

Figure 1 is a view partly in side elevation and partly in section of the device embodying the present invention showing the same applied to a shelf.

Figure 2 is a view in top plan of the bracket per se.

Figure 3 is a transverse sectional view taken upon the line 3—3 of Figure 1.

Figure 4 is a transverse sectional view taken upon the line 4—4 of Figure 2.

Referring more particularly to the drawings the numeral 1 indicates a shelf in association with which the present supporting

bracket is shown, the bracket itself being indicated as a whole by the numeral 2.

As shown in Figure 2 the bracket comprises an elongated flat plate 3 having one end, its outer end, rounded as indicated at 4. Secured to one face of the plate 3 at the outer or rounded end and concentric therewith, is a split resilient ring 5 the free ends 6 of which are disposed upon opposite sides of the longitudinal center of the plate remote from the rounded outer end thereof. The band or ring 5 has secured to its lower edge diametrically opposite the split portion the securing lugs 7 which are riveted or otherwise suitably fastened to the plate 3 at the outer end thereof as shown.

Adjacent each split end 6 of the article holding band 5 the plate is provided with a slot 8. Each free end of the split band or ring 5 has formed integral therewith on its lower edge a guide lug 9 which extends through the adjacent slot 8 and engages the under face of the plate 3 as shown in Figures 1 and 2. From this it will be readily understood that the free ends of the band 5 may be swung apart to enlarge the band if necessary to receive an article such for example as the container 10 shown in Figure 1 and the lugs 9 which prevent the free ends of the band from coming away from the body of the plate will be allowed the necessary unrestricted movement which they must have in order to enlarge the band, by the slots 8 through which the lugs extend.

At the radial center of the container holding band 5 there is secured to the under face of the plate 3 by a rivet 11, or other suitable means, a relatively long resilient bar 12 which extends longitudinally of the under face of the plate toward the inner end thereof to a point substantially midway between the ends where an aperture 13 is formed. The resilient bar 12 at this point is turned to extend upwardly through the aperture 13 as indicated at 14 when it is again turned to form the hooked terminal 15 disposed above the top of the plate 3 a sufficient distance to permit of the insertion between it and the plate of the edge of the shelf 1, the plate positioning against the under surface of the 100

shelf while the hooked terminal 15 engages the top surface thereof.

The upwardly directed portion 14 of the bar 12 carries a tongue 16 beneath the plate 3 between which and the plate is disposed the cam flange 17 of a pivoted latch member 18. This latch member 18 as shown is secured to the plate 3 by a rivet or similar means as indicated at 19 and has a finger 20 by which it may be grasped to facilitate its rotation.

From the foregoing description it will be readily seen that when the inner end of the plate 3 is disposed beneath the shelf 1 with the hooked end 15 of the securing bar 12 disposed over the shelf surface, upon rotating the catch 18 the circular cam flange 17, which is arranged concentric with the pivot point 19, will ride against the tongue 16 of the securing bar and cause the hooked end 20 of the bar to be drawn down toward the plate and to bite into the adjacent shelf. By this means the bracket plate is firmly secured to the shelf with the outer end in position to receive a container in the manner described.

Having thus described our invention, what we claim is:

1. A shelf attached article support comprising a supporting body adapted to have a portion thereof disposed against the under face of a shelf, a gripping element resiliently secured to the under face of the body and adapted to engage the top face of the shelf to maintain the body in position thereagainst, and a holding means carried by the body for maintaining an article in position thereon.

2. A supporting bracket of the character described, comprising an elongated body having, when in use, one end disposed against the under face of a shelf, a gripping element resiliently secured to the under face of the body adapted to engage the upper face of the shelf, means on the under face of the body for increasing or decreasing the pressure of said gripping element on the shelf, and means carried by the first mentioned body at the other end thereof for holding an article thereon.

3. A supporting bracket of the character described, comprising an elongated body having, when in use, one end disposed against the under face of a shelf, a gripping element resiliently secured to the under face of the body adapted to engage the upper face of the shelf, means on the under face of the body for increasing or decreasing the pressure of said gripping element on the shelf, and article holding means carried by the first mentioned body at the other end thereof, said last means being adjustable to receive and hold articles of different sizes.

4. An article supporting bracket comprising a plate designed to engage at one end the under face of a supporting shelf, a shiftable

clamping element movable relative to the upper face of the plate for engaging the opposite face of the shelf, a rotary latch element carried by the body having an arcuate portion engaging the gripping element and adapted to actuate the same in one direction on rotation of the latch, and means carried by the body at the other end thereof for engaging and holding an article placed on the body.

5. An article support comprising an elongated plate having an inner and an outer end, said inner end being positioned against the under surface of a shelf when the support is in use, a clamping element shiftable relative to the plate for securing the plate to a supporting shelf, a pivoted cam element carried by the plate and connected with the clamp for actuation of the same, and an article holding body carried by the plate at its outer end.

6. An article support comprising an elongated plate, a resilient bar secured to one face of the plate and extending longitudinally thereof to a point intermediate the ends of the plate, said bar terminating at its free end in an upwardly projecting portion extending through an aperture in the plate and terminating in a gripping tongue movable with the bar relative to the plate, a lug carried by the upturned portion of the bar at the side of the plate opposite the gripping tongue, a pivotally mounted member having a cam flange arranged to work between said lug and the plate to move the tongue toward the plate for the purpose of gripping a support arranged between the tongue and plate, and a body holding element mounted upon that surface of the plate adjacent the gripping tongue.

In testimony whereof we hereunto affix our signatures.

FRANCIS W. FURSTENBERGER.
